UNITED STATES PATENT OFFICE.

JACOB G. FOX, OF BAY CITY, ASSIGNOR OF A PART TO ISAAC M. HENDERSON AND EDMUND W. HENDERSON, OF DETROIT, AND GEORGE P. CHAPMAN AND HORACE E. HATCH, OF LAPEER, MICHIGAN.

KNOB ATTACHMENT.

SPECIFICATION forming part of Letters Patent No. 269,516, dated December 26, 1882.

Application filed August 24, 1882. (Model.)

To all whom it may concern:

Be it known that I, JACOB G. FOX, a citizen of the United States, residing at Bay City, in the county of Bay and State of Michigan, have 5 invented a new and Improved Means for Attaching Door-Knobs to Spindles, of which the following is a specification.

The nature of my invention consists in certain features of construction combined, as will 10 be hereinafter set forth, and particularly pointed out in the claim.

The object of my invention is to overcome the inconvenience and annoyance of knobs becoming detached from their spindles by sudden 15 jars and frequent turning, and this object I attain by the means illustrated in the accompanying drawings, in which—

Figure 1 is a longitudinal section through the detachable knob, and showing also the spindle and the knob, which is permanently fastened to it, the spindle being so turned as to show three of its corners; and Fig. 2 is a transverse section through the knob-spindle, and showing the detachable knob in end elevation; 25 and Fig. 3 is a modification of the internally-screw-threaded tube.

A in the drawings represents a door-knob spindle, with a knob, B, permanently fastened to it in any suitable manner. This spindle is 30 of square or prismatic form, and provided with segments of a screw-thread, a , on its corners, as shown.

B' represents a detachable knob, which is provided with a revolving tube, b, having a 35 screw-thread, b' , on its inner surface, and a stop-collar, b^2 , on its periphery, near its inner end, and a solid end, b^3 , in which a nick, b^4 , for a screw-driver, is cut, as shown. The screw-threaded tube b is fitted in the central bore of 40 the knob B', its collar b^2 abutting against the inner face of the knob, while its solid end b^3 extends out beyond the outer face of the same through a riveting-plate, C, as shown.

Against the collar b^2 a rosette-shaped confining-plate, C', is applied, this plate being provided with a shank having a central prismatic passage, f, which terminates in a cylindrical socket, f', as shown. The prismatic passage corresponds to the shape and size of the

spindle, while the socket corresponds to the 50 shape and size of the collar.

The plates C and C' are united to the knob B' by rivets g, and thus confine the revolving tube b in place and against longitudinal movement without interfering with its revolution. 55

In order to fasten the knobs B and B' together, the spindle A, having the permanent knob B attached to it, is passed through the door and into the square opening f of the shank of the riveting-plate C' of knob B'. Then by 60 placing a screw-driver in the nick b^4 of the protruding end of the revolving tube b and turning the same the knobs will be drawn together by the segmental threads a of the spindle A screwing into the threads of said tube b, and 65 thus drawn together they will be securely held, as the square spindle cannot turn in the knob, and the tube b will not be turned independently of the knob or spindle when the knobs are operated for the usual purpose. 70

A wearing-bearing for the revolving tube b may be provided within the bore of the knob B', if desired; and instead of nicking the solid end of the revolving internally-screw-threaded tube b, said end of the tube may be provided 75 with a button of prismatic or circular form, so that the tube may be operated from the outside of the knob by hand or otherwise.

The invention I have described and shown affords a very convenient and permanent fastening for the detachable knob B' without adding great expense. 80

In Fig. 3 I have shown an equivalent plan of construction to that shown in the other figures, the internally screw-threaded tube being 85 provided with a shoulder, b^5 , near its nicked end, and when this construction is adopted the collar b^2 will be dispensed with, as the shoulder will prevent the tube moving longitudinally. 90

The confining-plate with prismatic passage in its shank may be fastened in position by any of the well-known means, and my invention is not confined to the precise style or construction of knob shown and described.

My invention differs from ordinary knobs provided with a fixing-screw inserted from the outer side of the knob, and which screw can be 95

turned backward out of the knob. In my knob the fixing-screw serves both as a nut for the spindle and as a means for fixing the knob upon the spindle, and when the knob is in use 5 the fixing-screw cannot move longitudinally in either direction, and in this respect it is novel and more advantageous than ordinary knobs.

What I claim as my invention, and desire to secure by Letters Patent, is—

10 The combination, with a knob-spindle of prismatic form and screw-threaded at its corners, of a detachable knob having a shank on its confining-plate, with prismatic passage in

it, and provided with a center tube, which is screw-threaded internally, made smooth and 15 cylindrical externally, provided with means for holding it, while the knob is in position, from longitudinal movement in either direction, while it is allowed to revolve within the knob, and constructed with a protruding end, by 20 which it is operated from the outside of the knob, substantially as described.

JACOB G. FOX.
